UNITED STATES PATENT OFFICE.

GRANT RAPP, OF JERSEY CITY, NEW JERSEY, ASSIGNOR TO THE HARTFORD CARPET COMPANY, OF HARTFORD, CONNECTICUT.

DESIGN FOR A CARPET.

SPECIFICATION forming part of Design No. 14,509, dated December 25, 1882.

Application filed July 23, 1883. Term of patent 3½ years.

To all whom it may concern:

Be it known that I, GRANT RAPP, of Jersey City, New Jersey, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

15 The ground *a* is in different portions va-

riously ornamented with small ornamental work, as shown. Over this ground are disposed four large flower-groups, A, B, C, and D, and the small group E, all clearly shown in the photograph, each consisting of central 20 masses of flowers and leaves with irregularly-projecting leaf and blossom sprays and clusters.

I claim—

The design for a carpet, substantially as 25 shown and described.

GRANT RAPP.
